UNITED STATES PATENT OFFICE.

ARTHUR L. HALLIDAY, OF BROOKLYN, NEW YORK, ASSIGNOR TO THE
BIGELOW CARPET COMPANY, OF CLINTON, MASSACHUSETTS.

DESIGN FOR A CARPET.

SPECIFICATION forming part of Design No. 19,344, dated October 8, 1889.

Application filed September 10, 1889. Serial No. 323,559. Term of patent 3½ years.

To all whom it may concern:

Be it known that I, ARTHUR L. HALLIDAY, a subject of the Queen of Great Britain, residing at Brooklyn, Kings county, New York, 5 have invented a new and original Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face 15 view of a carpet showing my new design.

My design consists of the body A and the border B. The body A is composed of flower forms, some arranged in groups and others separate, and a background of somewhat 20 shield-shaped figures. The border B has an

inner margin consisting of a row of flower forms and an outer margin having a row of overlapping flower forms and containing smaller ornaments. Between the marginal ornaments flower forms are disposed, some in 25 groups and some separately; and the background contains somewhat shield-shaped figures.

What I claim, and desire to secure by Letters Patent, is—

1. A design for carpets, consisting of the body A, substantially as shown.
2. A design for carpets, consisting of the border B, substantially as shown.
3. A design for carpets, consisting of the 35 body A and border B, substantially as shown.

ARTHUR L. HALLIDAY.
